UNITED STATES PATENT OFFICE.

ARTHUR B. WARING, OF NEW YORK, N. Y.

METHOD OF DECORATING FELT HATS.

1,115,043.

Specification of Letters Patent. Patented Oct. 27, 1914.

Application filed December 6, 1912. Serial No. 735,184.

To all whom it may concern:

Be it known that I, ARTHUR B. WARING, a citizen of the United States, and a resident of the city, county, and State of New York, have invented certain new and useful Improvements in Methods of Decorating Felt Hats, of which the following is a specification, reference being had to the accompanying drawings, forming a part thereof.

10 My invention relates to a novel method of decorating felt hats and its object is to provide a simple way of impressing designs upon folded hat bodies which shall appear upon the finished hats in symmetrical form.

15 I will describe my invention in the following specification and point out the novel features thereof in appended claims.

Referring to the drawings, Figure 1 is a front elevation of a press with a printing 20 block and a hat body thereon. In Fig. 2 a folded hat body is shown in side elevation with a design printed thereon. Fig. 3 is a similar view on a smaller scale showing a design of different pattern. In Fig. 4 the 25 hat body illustrated in Fig. 2 is shown in plan view on a smaller scale expanded into conical form.

Like characters of reference indicate corresponding parts in all the figures. 30 Felt hat bodies are made in the form of a hollow cone with its apex rounded or of dome shape. Such a hat body may be folded into a flat sector shape as shown at 10 in Figs. 1, 2 and 3. In this condition it will 35 be folded along two converging lines 11 and 12. When thus folded a design may be printed upon it. I am aware that attempts to print designs upon folded hat bodies have been made heretofore, but in such cases there 40 has always been an unsightly break in the design along the lines of fold. I have devised a way by which this serious defect may be overcome. The principle which I utilize is to make a symmetrical design for covering 45 nearly all of the hat body with certain unprinted portions of the design registering with the folds. In carrying out this method the hat bodies are folded or pressed into a predetermined shape and laid upon a guide 50 bed 13. Then the printing block 14 which has upon it in relief the design to be reproduced is covered with the dye or ink which is to be transferred to the hat body and is 55 forced down onto the hat body by any desired means. It is important however, that the printing block should register properly

with the folds of the hat body. It may therefore be supported in a sliding frame 15 suitably guided by rods 16 in definite relation to the bed 13 which holds the hat body. 60

In the particular pattern illustrated in Figs. 2 and 4 the design is repeated between equally spaced pairs of parallel lines 20, 21 each of which pairs is substantially radially disposed. At the folded edge 11 but one of 65 these lines,—that designated by 21^A,—is provided, and at the other edge is one line 20^A. These outer lines are parallel with the folded edges and the distance from each of these lines to its respective edge is substantially 70 one half the distance between the other lines 20, 21. Both sides of the folded hat body are thus printed and the result is that when the hat body is expanded into its conical form a symmetrical design will appear 75 thereon with the same appearance at the portions which had been folded, as upon other portions. Such a hat body can then be shaped into crown and brim portions in the usual way. 80

It is to be understood that the hat bodies may be turned inside out so that all of its surfaces may be printed.

It is well within the scope of this invention to reproduce the design upon the folded 85 hat bodies by other means than printing with inks or dyes. For example, the printing block may be made of metal and heated and its design impressed upon the hat body at such heat and pressure as to scorch the 90 fabric; or if desired the design may be stenciled upon the folded hat body either by brush or spray stenciling or by dipping.

By the use of this method, hats of attractive appearance may be made. The designs 95 or patterns may be endlessly varied, and the appearance of hats of woven fabrics or of hats with ornamental stitching may be simulated in felt hats and without stitching.

The pattern illustrated in Fig. 4 is added 100 to show that I am not limited to designs repeated between radial lines. It is only necessary that the design be such as to have no printed portion along the lines of fold and be either symmetrical to such unprinted 105 lines or so proportioned that such unprinted lines become properly balanced parts of the complete design.

What I claim is:

1. The method of decorating felt hats 110 which comprises symmetrically folding a hat body and reproducing upon its outer

surfaces between said folds, a symmetrical design of which the folded lines form a part.

2. The method of decorating felt hats which comprises symmetrically folding a hat body and impressing upon its outer surfaces between said folds, a design of which the folded lines form a part.

3. The method of decorating felt hats which comprises folding a conical hat body 10 along diametrically opposed lines into a flat form, and reproducing such a design upon each of its two outer surfaces between said folds, that a single symmetrical design, of which the folded lines form a part is produced on the hat.

4. The method of decorating felt hats which comprises folding a conical hat body along diametrically opposed lines into a flat form, and printing upon its outer surfaces a design repeated between substantially radial 20 lines two of which are on the lines of the folds.

In witness whereof, I have hereunto set my hand this 4th day of December, in the year 1912.

ARTHUR B. WARING.
